[57] CLAIM

The ornamental design for a golf club support stand and towel holder, as shown and described.

DESCRIPTION

FIG. 1 is a front elevational view of a golf club support stand and towel holder showing our new design;
FIG. 2 is a right side elevational view thereof;
FIG. 3 is a rear elevational view thereof;
FIG. 4 is a left side elevational view thereof;
FIG. 5 is a top plan view thereof;
FIG. 6 is a bottom plan view thereof;
FIG. 7 is a top plan view of a second embodiment thereof, the only difference from that of the first embodiment residing in the configuration of the top element; and,
FIG. 8 is a top plan view of a third embodiment thereof, the only difference from that of the first embodiment residing in the configuration of the top element.
